US00D861385S

(12) **United States Design Patent** (10) Patent No.: **US D861,385 S**
Gorman et al. (45) Date of Patent: ** Oct. 1, 2019

(54) **DISPLAY STRUCTURE**(71) Applicant: **Apple Inc.**, Cupertino, CA (US)(72) Inventors: **Michael Gorman**, Dublin, CA (US); **Manuel Reza**, Sunnyvale, CA (US); **Federico F. Tio**, Santa Cruz, CA (US); **Kevin Fenton Smeds**, San Francisco, CA (US); **Edmond Kuan**, San Francisco, CA (US)(73) Assignee: **Apple Inc.**, Cupertino, CA (US)(**) Term: **15 Years**(21) Appl. No.: **29/654,512**(22) Filed: **Jun. 25, 2018****Related U.S. Application Data**

(63) Continuation of application No. 29/559,270, filed on Mar. 25, 2016, now Pat. No. Des. 821,117.

(51) **LOC (12) Cl.** ..... **06-04**(52) **U.S. Cl.**USPC ..... **D6/661**(58) **Field of Classification Search**USPC D6/560, 642, 654.1, 657, 661, 662, 664, D6/672, 673, 675, 675.1, 675.3, 699; D34/20; D30/101

Japanese Patent Office document HB24003431, reported by JPO as dated Mar. 2012, p. 88.

Primary Examiner — Kevin K Rudzinski

Assistant Examiner — Paul D Bohannon

(74) Attorney, Agent, or Firm — Sterne, Kessler, Goldstein & Fox PLLC.

(57) **CLAIM**

The ornamental design for a display structure, as shown and described.

DESCRIPTION

FIG. 1 is a top front perspective view of a display structure showing the claimed design;

FIG. 2 is a bottom front perspective view thereof;

FIG. 3 is a front view thereof;

FIG. 4 is a right side view thereof;

FIG. 5 is a left side view thereof; and,

FIG. 6 is a top view thereof.

The dashed broken lines in the figures show portions of the display structure that form no part of the claimed design. The oblique shade lines in the figures show reflectivity, transparency, or translucency.
